(57) **CLAIM**

The ornamental design for a hermetic terminal, as shown and described.

DESCRIPTION

FIG. 1 is a front view of a hermetic terminal in accordance with the present design;

FIG. 2 is a back view thereof;

FIG. 3 is a right side view thereof;

FIG. 4 is a left side view thereof;

FIG. 5 is a top view thereof;

FIG. 6 is a bottom view thereof;

FIG. 7 is a cross-sectional view taken along line VII-VII of FIG. 5;

FIG. 8 is a top perspective view thereof; and,

FIG. 9 is a bottom perspective view thereof.

The dash-dot broken lines in the drawings illustrate the bounds of the claim and form no part of the claimed design. The dash-dash broken lines in the drawings illustrate portions of the article that form no part of the claimed design.

1 Claim, 5 Drawing Sheets
